ment Company, Streator, Ill., a syndicate

Application April 23, 1931. Serial No. 532,239

18 Claims. (Cl. 153—16)

This invention relates to a press brake. It has for one object to provide a machine capable of bending metal or other material. Another object is to provide, in connection with such a machine, means for bending a given piece of material a number of times. Another object is to provide, in connection with such an apparatus, means for operating its various parts automatically. Another object is to provide, in connection with such a machine, material holding means and material bending means and separate operating mechanism for each of said means.

Other objects will appear from time to time in the specification and claims.

15 The invention is illustrated more or less diagrammatically in the accompanying drawings, wherein:—

Figure 1 is a front elevation of the press brake, with parts in section;

20 Figure 2 is a longitudinal vertical cross section, taken at line 2—2 of Figure 1 and showing a portion of the material handling means as well;

Figure 3 is a sectional view, showing one type of bend which can be made by the machine;

25 Figure 4 is a longitudinal vertical cross section, generally similar to Figure 2, showing the parts in a different position, in which the material holding member is raised;

Figure 5 is a longitudinal vertical cross sectional detail, taken on an enlarged scale, showing the bending parts at or near the completion of a bending movement;

30 Figure 6 is a side elevation on an enlarged scale, showing particularly the controlling mechanism;

Figure 7 is an elevational view taken at right angles with respect to Figure 6, showing the same parts and looking in the direction of the arrow in Figure 6;

40 Figure 8 is a detailed longitudinal horizontal cross section, taken at line 8—8 of Figure 6;

Figure 9 is a transverse vertical cross sectional detail, on an enlarged scale, taken at line 9—9 of Figure 6;

45 Figure 10 is a longitudinal vertical cross sectional detail, taken at line 10—10 of Figure 9;

Figure 11 is a transverse vertical cross section, taken at line 11—11 of Figure 1, showing the hold-down cylinder in elevation;

50 Figure 12 is a detailed elevation of one side of the machine, showing the material holding assembly raised;

Figure 13 is a longitudinal vertical cross sectional detail, taken on an enlarged scale at line 55 13—13 of Figure 12;

Figure 14 is a longitudinal horizontal cross sectional detail, taken at line 14—14 of Figure 4, and showing, in elevation, the operating means for the bending apron; and

60 Figure 15 is a piping diagram illustrating diagrammatically the operating means and the piping connections therefor.

Like parts are designated by like characters throughout the specification and drawings.

A is a floor or foundation upon which the machine is positioned. It may be of any suitable material or nature. For the purposes of the invention, it is sufficient that the machine be supported upon a firm base, adequate to carry its weight and of sufficient strength to endure 65 shocks and jars incident to the operation of the machine.

The frame of the machine is made up essentially of two pairs of vertically positioned members B, B. These members may be channels as 75 shown. They are suitably secured to the base or foundation and each pair is preferably joined adjacent its upper ends, at least, by cross members B¹. At their lower ends the members B are joined by laterally extending plates B². Projecting outwardly from the members B² and lying in a generally horizontal position, are supports B³ which, as indicated particularly in Figure 6, may be made up of pairs of channels joined together, back to back. The members B³ serve to 80 support portions of the operating mechanism. A bed supporting member B⁴ which may be an I-beam, as shown for example in Figures 2, 4 and 5, extends in a generally horizontal position across between the two pairs of vertical supports 85 B and is suitably fastened to them. On its upper surface, it carries a laterally extended bed plate B⁵. B⁶ is a bracing member joined to the bed plate B⁵ and the bed support B⁴. Fastened to the rear or right hand members B, as shown for 90 example in Figures 2, 4, 5 and 6, are side frame members B⁷. These members are provided on their under surfaces with rack portions B⁸. At their rear ends they are supported by members B⁹ and they are provided with means for receiving guiding and placing members B¹⁰ which are removably positioned upon them for reasons 95 which will be described below.

C is a bending apron. Along its upper edge it carries an angle member C¹ which provides a 105 flange at the upper edge. At its sides the apron C is fastened to and supported by hinge members C² which are themselves hinged to the forward or left hand members B, as indicated for example in Figure 2, as at C³. In its rear the 110

apron C has secured to it an angle C⁴ which may have one or more bearing supports C⁵ in which are positioned pins C⁶, upon each of which is pivotally mounted a link C⁷. C⁸ is a carriage member upon which the opposite ends of the links C⁷ are pivoted. The carriage member may carry rollers C⁹ which are run in tracks C¹⁰, fixed or supported upon the foundation A. Extending forwardly or to the left, as shown in the figures, 5 from the carriage member C⁸ are frame members C¹¹ which carry a rod C¹² upon each end of which is positioned a roller C¹³. These rollers, like the rollers C⁹ are positioned to run in the tracks C¹⁰. Fastened to the rod C¹² is one end of 10 a piston rod C¹⁴ which is fastened to a piston C¹⁵ which is positioned within an hydraulic cylinder C¹⁶. The cylinder is arranged to operate the piston and to move it back and forth and thus to move the carriage C⁸ and its associated parts, 15 and so to move the apron up and down, suitable hydraulic connections being made to the cylinder to cause the back and forth movement of the piston within it. The cylinder is fastened to any suitable fixed support and, as here shown, is fastened to the foundation or floor A. 20

25 Fixed on the outside of the rear or right hand member B, as shown in the figures, is a rack D. A pair of channels D¹ are fastened together and these channels are mounted to move up and down along the rack and along the members B, in a manner and by means which will be described below. As will be noticed, particularly from Figure 12, and generally from a number of the other figures, the members D¹ are perforated 30 as at D² and may carry a sleeve-like member D³. The members are spaced apart sufficiently to receive a plate D⁴ which extends above them and stops short of their lower edge. This member is also correspondingly perforated to receive the sleeves D³ and the parts are held in position by 35 bolts D⁵ and nuts D⁶. At their lower edges the members D¹ have fixed to them a plate D⁷ which is provided with an inclined front edge D⁸. It may carry in its rear a spacing pin or member D⁹ and has fixed to its lower surface, and preferably removably, a contact plate D¹⁰. At its outer ends the plate D⁴ carries projections D¹¹, to each of which is fastened a piston rod D¹² which is fastened to a piston running in an hydraulic cylinder D¹³ which is itself supported upon one 40 of the members B³. Suitable hydraulic connections are provided for moving the piston up and down. Pivottally connected to the ends of the plates D⁴ are hooks D¹⁴ which are preferably double, as shown especially in Figure 11. Each 45 is provided with a cam portion or nose D¹⁵ adapted to contact a cam member D¹⁶ which is fixed adjacent the plate D⁴ to one of the members B. The plate D⁴ is provided adjacent each 50 of its ends with a perforation or opening D¹⁷, through which projects a pinion D¹⁸ positioned to engage the rack D. The pinions D¹⁸ are carried on a shaft D¹⁹ which is journaled in suitable bearings on the plate D⁴ or on the members D¹. D²⁰ is an hydraulic pull-down cylinder, 55 within which is mounted a piston. Suitable hydraulic connections are provided whereby the piston may be moved up and down. A piston rod D²¹ projects from the cylinder and is provided adjacent its top with a hook engaging member D²² by means of which the hook D¹⁴ 60 may engage the member D²².

65 For purposes of illustration, a plate E, which is being bent, is shown in several of the figures. As shown in Figure 2, the plate has not yet been bent

or otherwise acted upon. It is being inserted into the machine. In Figure 4 the plate is shown as having been bent to provide a flange or relatively narrow bend E¹. As shown in Figure 5, the plate has been further bent to provide a bent portion E² 80 and as a result of this, the flange E¹ is bent back generally parallel to the main body of the plate. As shown in Figure 3, each side of the plate has been bent to provide a flange E¹ and a portion E² and the plate has been further bent to provide other portions E³. The form shown in Figure 3 85 is suitable for use as a receptacle or dumping body. Such a member may be completed by providing an end plate, to close one end, and an end plate or gate or other closure, to close the other 90 end.

95 Many different means of handling plate and other shapes which are to be bent in the machine will suggest themselves. Only one is shown and it is shown diagrammatically herewith, as its particular details form no particular part of the present invention. It is sufficient for the purposes of the present invention that means be provided to engage and support the plate or other shape which is being worked upon.

100 F represents a track upon which a carriage F¹ is supported by means of rollers or wheels F². From this carriage depends hoisting and supporting members F³, F⁴. These may embody electrical, mechanical or hydraulic parts and controlling and actuating connections F⁵ may be made. These parts may be of any suitable design. A trapeze-like frame F⁶ may depend from the supporting carriage. It may have separated ends which carry clamps F⁷, the clamps 110 being hydraulically or otherwise actuated. Thus two clamps may be used, one to engage the plate E on each side. For convenience it is frequently preferable to engage the plate at about its middle point.

115 Co-operating with the trapeze-like arrangement is a carriage mounted to run along the frame members B⁷. This carriage comprises side portions G, each of which has at its top a pair of rollers G¹ which are preferably flanged and arranged to run upon the upper surface of the members B⁷ which serve as tracks. A shaft G² extends across the assembly from one side of the carriage to the other and carries adjacent each end a pinion G³ which meshes with the rack portions B⁸ of the members B⁷. A hand wheel or turning member G⁴ is provided to rotate the shaft G² and thus to rotate the pinions G³ and move the carriage back and forth along the members B⁷. A pivotally mounted dog G⁵ is positioned on the frame members which support the rollers G¹ and this dog may be moved to engage one of the notches in the notched member B¹⁰. The trapeze is arranged to engage the carriage and thus, when the plate is carried by the trapeze and the trapeze itself is moved into engagement with the carriage, the carriage may then be moved and will carry the plate with it. As explained above, any form of mechanism for carrying, moving and adjusting the plate may be used in connection with the device of the present invention. The trapeze structure, just briefly described, is merely one suitable form. The detachable notched member B¹⁰ is provided with notches suitable for the particular bends which it is desired to give to any plate and for each particular operation the carriage is moved so that the dog G⁵ engages a given notch and the plate is thus carried to a suitable position for making 140 145 150

the particular bend which it is desired at that time to make.

For ordinary purposes, when it is desired to bend a member in the machine, it is put in position upon the bed plate and is gripped and held in the position by the hold-down member which is held in position by the hydraulic cylinders D²⁰. The apron C, with its flange C¹, is then raised toward the position shown in dotted lines in Figure 2, or to a position such as that shown in full lines in Figure 5, and the bend is accomplished as shown in the latter figure. The movement of the apron is stopped at the desired point when the bend has been accomplished. The apron is then usually lowered and the hold-down member raised and the plate may be removed from the machine entirely or else moved for subsequent bending or further treatment. These operations and the operations of the hydraulic cylinders which accomplish them may be controlled manually or in any suitable manner and by any desirable mechanism. In the present case a mechanism is shown which is in some of its operations automatic. This controlling and regulating mechanism will now be described.

Ordinarily there is one control assembly and for convenience it is all mounted upon one side of the press. In the form shown in Figure 1, the left hand hinge C³ is provided with a pin or shaft H, which, by means of a pin or spline H¹, is fastened to the member C² so that it moves with it. Thus, as the bending apron moves, it moves the pin H with it. Upon the outer end of that pin is positioned a sprocket H². A stub shaft H³ is journaled in a suitable bearing which may be mounted upon one of the vertical side frame members B and carries an idler sprocket H⁴ which engages a chain H⁵ which is positioned about the sprocket H². H⁶ is a stub shaft journaled in suitable bearings preferably supported from the vertical member B. It carries a sprocket H⁷ which is in mesh with the chain H⁵. The sprocket pinion H⁷ has fastened to it, to move with it, a pinion H⁸.

I (Fig. 9) is a stub shaft having a reduced portion I¹ and being supported in a suitable bearing I², which is supported on one of the uprights B. At one end it has a retaining member I³ fastened upon it and intermediate its ends it has a spacing collar I⁴ fastened upon it. Fixed upon it also is a member I⁵ which carries a pinion I⁶ which is fastened to an arm I⁷. The pinion I⁶ meshes with the pinion H⁸.

Positioned about the reduced end I¹ of the shaft I is a short stub shaft J. It has on its outer end a retaining portion J¹ and it carries a sleeve-like member J² which is fixed to it to move with it and which has formed upon it a worm gear J³. Movably mounted upon the sleeve J² is a housing J⁴ which encloses a worm J⁵ which meshes with the worm gear J³. The housing carries an index pointer J⁶ and preferably generally opposite the pointer J⁶, it also carries a stop member J⁷. An index wheel or plate J⁸ is mounted upon the stub shaft J to move with it. An extension J⁹ which may be formed with or welded or otherwise fastened to the housing J⁴ is positioned upon, fixed to and supported by a stub shaft J¹⁰. J¹¹ is a shaft journaled in the housing J⁴ and carrying the worm J⁵. A hand wheel or crank J¹² is provided for it, by means of which it may be rotated. J¹³ is a stop mounted on the disc or plate J⁸ and positioned to be engaged by the arm I⁷.

The shaft J¹⁰ is supported in a bearing K, formed in a supporting bracket K¹ which is supported upon one of the upright members B. K² is a stop formed on the supporting bracket K¹ and positioned to be engaged by the stop J⁷, of the housing J⁴, when the latter moves into contact with it.

L is a lever fixed to the stub shaft J¹⁰. Fastened to this lever at one end is a spring L¹ which is fastened at its other end to some fixed point, such as a pin L² which is itself fastened to one of the vertical frame members B. Fastened to the outer end of the lever L is a link L³ which is itself fastened to a valve handle L⁴ which controls the movement of a valve L⁵. A connection or pipe L⁶ runs from the valve L⁵ to the hydraulic cylinder L⁷. L⁸ is a pipe leading from the cylinder L⁷ at the end opposite to the connection L⁶. It permits fluid to escape from the cylinder. Within the cylinder L⁷ is a piston L⁹ which has connected to it a piston rod L¹⁰ which projects beyond the cylinder and by means of a link L¹¹ is connected to the handle L¹² of a valve L¹³ which is formed as shown diagrammatically in Figure 15 and is connected by conduits which will be described below so that it can operate the cylinder C¹⁶ to raise and lower the bending apron. This operation is automatic or semi-automatic and its details will be described below.

In order to understand the operation of the various hydraulic mechanisms, whether this operation be automatically, semi-automatically or manually controlled, attention is called to Figure 15, which is a diagrammatic showing of the parts and their connections.

In that figure M is a reservoir for oil or other liquid used in the hydraulic system. M¹ is a pump. A supply pipe M² leads from the reservoir to the pump. M³ is an accumulator in which a piston M⁴ is positioned. The piston rod M⁵ projects beyond the cylinder and carries a weight M⁶ of sufficient size to maintain the desired pressure within the accumulator. A connection or conduit M⁷ runs from the pump to a valve M⁸ and a conduit M⁹ runs from the pump. Another conduit M¹⁰ connects the accumulator cylinder with the conduit M⁹.

Branch conduits N, N¹ and N² lead from the conduit or pipe M⁹ and are provided, respectively, with valves N³, N⁴ and N⁵. The conduit N, after leaving the valve N³, runs to a two-way valve N⁶ which is provided with a connecting conduit N⁷ which, through branches N⁸ N⁹ may supply liquid to the cylinders D²⁰. A conduit N⁹ leads from the opposite ends of the cylinders D²⁰ back to the valve N⁶. N¹⁰ is a fluid return conduit by means of which fluid which leaves the various hydraulic cylinders may be returned to the reservoir M. A branch N¹¹ leads from the valve N⁶ to the return conduit N¹⁰. The conduit N¹¹, after passing through the valve N⁴ leads to the two-way valve L¹³. From this valve a conduit N¹² leads to the cylinder C¹⁶. The conduit N¹³ leads from the opposite end of the cylinder C¹⁶ back to the valve L¹³ from which a connecting conduit N¹⁴ leads to the return pipe N¹⁰. The conduit N², after passing through the valve N⁵ leads to a two-way valve N¹⁵. From this valve a conduit N¹⁶ having a branch N¹⁷ leads to the two hydraulic cylinders D¹³ from each of which return conduits N¹⁸ lead to the main return conduit N¹⁰. N¹⁹ is a conduit connecting the pressure conduit M⁹ with the main return conduit N¹⁰. A valve N²⁰ is positioned in it. N²¹ is a connecting conduit running from the

main return conduit N^{10} to the valve M^8 in the main pressure conduit M^9 . The valve L^{13} is shown diagrammatically in Figure 15. It is indicated generally as the middle valve in Figures 6 and 7. The valve N^6 is the lowermost valve in Figures 6 and 7, while the valve N^{15} is the uppermost valve in Figures 6 and 7. In the form of the invention shown herewith, the valves N^6 and N^{15} are operated manually. The valve N^6 controls the operation of the main pull-down or hold-down cylinders D^{20} . It is manually controlled by a handle N^{22} . The valve N^{15} controls the operation of the cylinders D^{13} . In the form of the invention shown herewith, it also is manually controlled by a handle N^{23} . Thus the movement of the valve L^{13} is controlled automatically in response to a setting of the dial and so the amount of movement of the bending apron and, therefore, the amount of bend, is controlled automatically after the parts have been set for the desired bend. The operation and movement of the hold-down member, both as to raising and to lowering, is controlled manually. N^{24} is a conduit leading from the conduit N^{12} to the housing of the valve L^5 .

While we have herewith shown and described a practical operative device, nevertheless many changes might be made in the size, shape, number and disposition of parts without departing from the spirit of our invention and we wish, therefore, that our showing be taken as in a sense diagrammatic.

The use and operation of this invention are as follows:

35 The brake is designed for the bending of material. In the form shown herewith it is particularly adapted for use as a machine for bending sheets or plates, which are given several successive bends, some in a reverse direction with respect to other bends. The hold-down plate is given a very considerable travel so that a plate having been put in from the rear and bent may be removed to the rear for adjustment of repositioning for subsequent bending. This is possible even where a quite a large piece has been bent up. Heretofore, in press brakes of the type now on the market, where a piece of considerable width is bent up, for example a piece eighteen inches or more in width, it has been necessary to withdraw the plate from the front of the machine. If subsequent bends are to be made, this necessitates carrying the piece bodily around the machine and re-inserting it in a reverse direction from the rear. With our invention, the plate having been bent up, the hold-down member is raised, the plate is withdrawn to the rear and then reversed, turned over and otherwise re-positioned for further bending. By reason of this, the supporting and holding mechanism to which the plate is attached can remain attached to it throughout the entire operation and once the plate has been put into the holding mechanism it need not be removed from it or detached from it until the entire bending operation is completed and this is true even although the bending operation includes several bends on one edge and several other bends on an opposite edge and such bends may involve considerable widths of material. This will be the case in bending a plate into the shape shown in Figure 3. In shaping that plate, the supporting equipment is attached approximately at the middle of the plate. Ordinarily, for the purpose of convenience, the carriage which is mounted to run along the frame members B^7 is put into the position shown in Fig-

ure 2, with the dog G^5 engaging one of the notches in the plate B^{10} . The plate is temporarily positioned in the trapeze mechanism, the latter is put in engagement with the carriage and the plate is then moved forward until it contacts spacing pins D^9 . Usually the notches in the plate B^{10} are so positioned that for a given plate, when that plate is in contact with the spacing pins, the trapeze mechanism, if it is in position on the carriage as shown in Figure 2, will be at the center of the plate. The plate is then clamped to the trapeze mechanism, the hold-down member is raised, the plate is moved forward until the dog G^5 engages the next notch in the plate B^{10} , the hold-down member is then moved into position holding the plate, the apron C is raised by the hydraulic cylinder in a manner which will be described below. This raising is continued as far as necessary to give the desired bend and thus the bent portion E^1 is formed. When this bend is completed, the apron C is lowered, the hold-down member is raised, the carriage is moved forward until the dog engages the next notch, as for example, the notch shown in Figure 4, in which the dog lies. The hold-down member is then lowered, the apron C is raised to the position shown in Figure 5 to accomplish the second bending and to form the portion E^2 . The degree of bending, that is to say, the angle through which bending is carried out, may be anything from one degree to a maximum of more than 90° . The hold down member D^7 is given the inclined front face D^8 to permit this amount of bend. Subsequent bends might be made by moving the carriage forward, but to form the plate shown in Figure 3, the carriage with the plate will be moved rearwardly until the plate is entirely out of contact with the machine. The plate will then be reversed and moved forward again between the bed and the hold-down member, the carriage will be moved to the suitable notch, which is the next to the last, as shown in Figure 4, from that occupied by the dog G^5 as shown in that figure, the hold-down member is moved into position and a subsequent bend is carried out. In this fashion the machine operates to give almost any suitable number of successive bends and, as has been said, these may be in a direction reversed, one with respect to the other. The details of the operation of the mechanism itself will now be described. With the parts of the machine as shown in Figure 1, no bending is occurring and the hold-down member is in position. The details of the hold-down member are shown in Figure 13. As there shown, the plate D^4 is attached to the members D^1 which carry the lower member of the hold-down assembly D^{10} only at two points, namely, the bolts D^5 . Thus, when the plate D^4 is pulled down, the hold-down effect is transmitted through the bolts D^5 to the members D^1 and thence to the members D^7 and D^{10} . By this construction, the danger of warping or bending of that portion of the hold-down assembly which contacts the work to be held down is reduced. With the parts as shown in Figure 1, the hold-down assembly is gripped and held down by the large cylinders D^{20} . The hooks D^{14} , which are pivotally attached to the plate D^4 , are engaged with the member D^{22} of the piston rod D^{21} . A pull down on the piston to which this rod is attached pulls the hooks and the plate D^4 and the entire hold-down assembly and holds it in position. When it is desired to release the hold-down assembly and to raise it, the pistons to which the piston rods D^{21} are attached

80

are reversed, that is to say, moved upwardly. At first, the rod D^{21} contacts the bottom face of the plate D^4 and pushes the hold-down assembly up. If the movement is continued, the members D^{15} of the hooks D^{14} contact the cams D^{16} and the hooks are held, as indicated in dotted lines in Figure 12, out of engagement with the member D^{22} . If, for the purpose of the bend in question, it is necessary only to raise the hold-down assembly slightly, the heavy or large cylinder D^{20} will be used only. Where it is necessary to raise the hold-down assembly more, the cylinders D^{13} and their pistons and piston rods will be used, and in that case, pressure is applied to raise the pistons to which the piston rods D^{12} are attached, and the hold-down assembly is raised into the position shown in full lines in Figure 12. Equal movement of each side of the assembly is insured by the use of the shaft D^{19} which is journaled upon the plate D^4 , and which carries the pinions D^{18} which mesh with the racks D on the side members B . By means, therefore, of movement of the pistons which lie within the cylinders D^{13} of D^{20} the hold-down assembly is raised or lowered.

25 When the hold-down assembly returns to the hold down position after having been raised, the portions D^{15} of the hooks D^{14} pass below the cams D^{16} and the hooks then swing into the engaging position in which they engage the member D^{22} as shown in Figure 1. Pressure is then suitably applied in the cylinder D^{20} to pull down on the piston, the piston rod D^{21} and the hooks D^{14} and thus the hold down assembly is held in the holding position and the plate or other article 30 which is to be bent or shaped is held against displacement and rests on the bed plate B^5 or the bed assembly generally.

With the parts held in this position, bending of the plate may commence. Pressure is suitably applied in the cylinder C^{16} to force out the rod C^{14} and this carries forward the carriage made of the shaft C^{12} , the side members C^{11} and the rear cross member C^8 . The links C^7 which at their rear ends are pivoted on the cross member C^8 , are moved forward as the carriage is moved forward. At their forward ends these links are pivoted upon the apron C and thus forward movement of the carriage, that is to say, movement from right to left, as shown in Figure 2, 45 raises the apron C from the full line position of Figure 2 to the dotted line position of that figure. The apron carries the angular member C^1 which is in contact with the member to be bent and thus as the apron is swung or moved upwardly, the angular member C^1 contacts the material 50 and effects the bend. As shown in Figure 5, the apron C is in a raised position and a bend has just been accomplished. When the apron has been moved sufficiently to accomplish the desired 55 amount of bend, pressure is applied to the cylinder C^{16} to withdraw the piston C^{15} and thus the carriage and apron move again to the position shown in full lines in Figure 2, and shown also in Figure 4.

60 There is attached to one of the hinges which support the apron C , so as to rotate as the apron moves, a pinion H^2 . The purpose of this pinion is to provide means for automatic control so that the amount of movement of the apron C and consequently the amount of bending accomplished by it may be automatically controlled. This automatic control will now be described.

65 The main function of the automatic control is to provide an adjustable automatic apparatus by means of which the operator can set the con-

trolling mechanism so that the apron will move through a predetermined arc and will automatically stop at the end of that arc. Thus, the operator is not under the necessity of constantly watching the apron and the danger of allowing it to go too far or of stopping it too soon is removed. As a part of the automatic operating mechanism an hydraulic cylinder is used, which, at a predetermined adjustable point, is automatically actuated to move the lever which controls the pressure to cylinder C^{16} and thereby, of course, controls the movement of the apron C . This operating cylinder is the cylinder L^7 . It is shown in plan in Figure 8. It appears in side elevation in Figure 6 and in end elevation in Figure 7. It is illustrated diagrammatically in Figure 15. As described above, the pinion H^2 which is moved with the apron C , is connected to the pinion H^7 , carried upon the stub shaft H^6 . Mounted to move with the pinion H^7 is a second pinion H^8 . This pinion H^8 meshes with a pinion I^6 mounted to move with a shaft I which shaft also carries an arm I^7 . By means of this gearing, movement of the apron C causes corresponding movement of the arm I^7 . The thimble-like member J , which is movably mounted on the reduced extension I^1 of the shaft I , carries a plate J^8 , provided with markings. Fixedly mounted on the member J is a member J^2 , carrying a worm gear. A housing is movably mounted on the member J^2 . It encloses a worm which meshes with the worm gear and the housing is also provided with a pointer J^6 . A handle J^{12} is also provided for rotating the worm gear. The markings on the plate J^8 are arranged to indicate degrees 100 of motion of the apron C . When it is desired to set the apparatus to carry out bending, the handle J^{12} is rotated so as to rotate the worm. Since the housing which carries the worm is held against movement by the contact of the stop J^7 105 with the stop K^2 , the plate J^8 , which is fastened to the member which carries the gear J^3 , is rotated. This rotation is carried out until the desired adjustment has been made. If a plate or other piece of material to be acted upon is in 110 position, the machine is now ready for bending movement. The operation of bending is normally manually initiated. The lever or handle L^{12} which controls the operation of the valve L^{13} is moved to the full line position of Figure 115 120 125 130 135 140 145 150 8. In that position pressure passes through the valve L^{13} to move the piston C^{15} outwardly or to the left. The apron is thus raised, the pinion H^2 is rotated with it. Through the gearing shown in detail in Figure 10, the rotation of the pinion H^2 causes rotation of the arm I^7 . This arm moves clock-wise, as shown in Figure 10, or counter clock-wise, as shown in Figure 6. It moves until it strikes the stop J^{13} on the plate J^8 . The position of this stop with respect to the initial position of the arm I^7 is adjusted by the adjusting movement of the plate or disc J^8 , as above described. When the arm I^7 contacts the stop J^{13} , it moves the plate and since the worm gear and worm are locked together, it moves the parts which carry them, and the housing, in a counter clock-wise direction, as shown in Figure 6. In this movement the lever L is moved downwardly or counter clock-wise against the action of the spring L^1 which tends normally to hold it upward. This downward movement of the member L is transmitted by means of the link L^3 to the valve handle or lever L^4 , thus putting pressure into the cylinder L^7 to move the piston to the right as shown in Figures 6 and 8, and

75

thus to move the valve lever or handle L¹² into the dotted line position of Figure 8. This movement reverses the direction of flow of pressure to the cylinder C¹⁶ so that the movement of the piston in that cylinder is reversed. Thus the apron C is stopped and reversed and moved again to the initial position shown in full lines for example in Figure 6. The valve handle or lever L¹² will remain in the dotted line position of Figure 8. Reverse or downward movement of the apron C causes a corresponding movement of the pinion H² and the gearing which is attached to it. This frees the disc, the worm gear and housing for reverse or clock-wise movement as viewed in Figure 6, and these parts are then returned to their initial position by the spring L¹. The valve handle L¹² will remain in the dotted line position of Figure 8 and the parts will remain stationary. When it is desired to effect another bending movement, the valve handle L¹² is moved manually from the position shown in dotted lines in Figure 8 to the position shown in full lines in that figure. This movement moves the valve L¹³ into position to cause the piston C¹⁶ to move outwardly and thus to effect another bending operation.

The operation of the cylinders which move and control the movement of the hold-down assembly might be arranged automatically. In the particular form of the invention shown herewith the operation of these cylinders is controlled manually by the levers or handles N²² and N²³, which operate, respectively, valves N⁶ and N¹⁵.

We claim:

35. 1. In combination in a forming machine, a bed, a hold-down member, means for moving said member, and a material bending means movably mounted means for moving the same, and automatic means for controlling the amount of bending movement, and for causing the bending means, upon the completion of a predetermined adjustable amount of movement in the bending direction, to return to its initial position.
40. 2. In combination in a metal forming machine, a bed, a hold-down member, means for moving said member toward said bed and away from said bed, and a material bending means movably mounted with respect to said bed, means for moving the same, and automatic means for controlling the amount of bending movement and for causing the bending means, upon the completion of a predetermined adjustable amount of movement in the bending direction, to return to its initial position.
45. 3. In combination in a metal forming machine, a bed, a hold-down member, hydraulic means for holding said member in the down position, a bending part mounted for bending movement, means for moving it, adjustable automatic means for controlling its movement to cause it to move through a predetermined distance.
50. 4. In combination in a metal forming machine, a bed, a hold-down member, rapid hydraulic means for holding said member in the down position, a bending part mounted for bending movement, means for moving it, automatic means for controlling its movement to cause it to move through a predetermined adjustable distance, to stop, to reverse and to return to its initial position.
55. 5. In combination in a metal forming machine, a bed, a hold-down member, rapid hydraulic means for holding said member in the down position, a bending part mounted for bending movement, means for holding down the hold-down member, one adapted for use in holding down the hold-down means, a bending member and means for moving it.

bending part mounted for bending movement and means for moving it.

6. In combination in a metal forming machine, a bed, a hold-down member, hydraulic means for holding said member in the down position, said means adapted to raise the member, an additional raising member for the hold-down member, a bending part mounted for bending movement and means for moving it.

7. In combination in a metal forming machine, a bed, a hold-down member, hydraulic means for holding said member in the down position, said means adapted to raise the member, an additional raising member for the hold-down member, of greater travel than the first mentioned member, a bending part mounted for bending movement and means for moving it.

8. In combination in a metal forming machine, a bed, a hold-down member, rapid hydraulic means for holding said member in the down position, said means adapted to raise the member, a bending part mounted for bending movement, means for moving it, adjustable automatic means for controlling its movement to cause it to move through a predetermined distance.

9. In combination in a metal forming machine, a bed, a hold-down member, hydraulic means for holding said member in the down position, said means adapted to raise the member, an additional raising member for the hold-down member, a bending part mounted for bending movement, means for moving it, adjustable automatic means for controlling its movement to cause it to move through a predetermined distance, to stop, to reverse and to return to its initial position.

10. In combination in a metal forming machine, a bed, a hold-down member, hydraulic means for holding said member in the down position, said means adapted to raise the member, an additional raising member for the hold-down member, of greater travel than the first mentioned member, a bending part mounted for bending movement with respect to the bed, means for moving it, adjustable automatic means for controlling its movement to cause it to move through a predetermined distance, to stop, to reverse and to return to its initial position.

11. In combination in a material handling means, a bed, frame members extending above said bed, a hold-down member positioned to move along said frame members, means to equalize the movement of said hold-down member along said frame members, a bending member and means for moving it.

12. In combination in a material handling means, a bed, frame members extending above said bed, a hold-down member positioned to move along said frame members, means on said hold-down member and engaging portions of said frame members, to equalize the movement of said hold-down member along said frame members, a bending member and means for moving it.

13. In combination in a material handling means, a bed, frame members extending above said bed, a hold-down member positioned to move along said frame members, means on said hold-down member and engaging portions of said frame members, to equalize the movement of said hold-down member along said frame members, a plurality of means for raising said hold-down member, one adapted for use in holding down the hold-down means, a bending member and means for moving it.
